UNITED STATES PATENT OFFICE.

ADOLPH C. KLOPPING, OF TOLEDO, OHIO, ASSIGNOR OF ONE-HALF TO THE TOLEDO PARLOR FURNITURE COMPANY, OF TOLEDO, OHIO, A CORPORATION OF OHIO.

BED-DAVENPORT.

1,081,272.

Specification of Letters Patent.

Patented Dec. 9, 1913.

Application filed June 2, 1913. Serial No. 771,136.

To all whom it may concern:

Be it known that I, ADOLPH C. KLOPPING, a citizen of the United States, and a resident of Toledo, in the county of Lucas and State 5 of Ohio, have invented a certain new and useful Bed-Davenport; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 This invention relates particularly to improvements in the folding bed-frames of bed-davports and has for its object the provision of improved means which is automatically operable to lock a bed-frame 20 section and a supporting leg therefor in folded relation when the frame has been folded a predetermined extent, and to automatically release the same to permit an unfolding movement of the leg relative to its 25 carrying section when the frame has reached a predetermined point in its unfolding movements.

A further object of my invention is the 30 provision, in combination with a pair of relatively folding bed-frame sections, of improved means which is automatically operable to yieldingly lock the sections in spaced folded relation, and which does not depend on movements of the adjacent frame 35 supporting leg for its locking or releasing movements relative to the frame section.

Referring to the drawings, Figures 1 and 2 designate two adjoining sections of a folding bed-frame, which sections are foldably 40 connected at their adjacent ends by connecting links 3, or in any other suitable manner, and the outer section 1 having a supporting leg 4 pivoted to each side thereof 45 adjacent to its outer end, as at 5, for folding movements thereagainst, as indicated in the drawings.

Projecting upward from each side of the section 1 adjacent to its outer end portion is a catch member 6 which, in the present instance, is attached to the section side by 50 means of the leg pivot 5 and is prevented from movement relative to the section 1 by flanges or tongues 7, 7, which are bent inward from the opposite side edges of the 55 member 6 and project over the upper side

edge of the section 1. The outer end is provided with a substantially V-shaped notch 8 leading to a U-shape notch 9 for receiving a stud 10, which projects from the respective side of the frame section 2 in position for the notch end of the arm 6 to lower thereover as the section 1 is folded over the section 2. The V-shaped notch 8 forms a broadened mouth for the associated notch 9 to assist in guiding the stud 10 in the notch 65 9 as the arm 6 is lowered thereover, as is apparent.

A catch-member 11 is pivoted, as at 12, to one side of the arm 6 and extends outward from the pivot 12 at one side of the 70 notch 9 of the arm. The inner edge of the member 11 is transversely notched adjacent to its outer end with such notch in register with the inner end portion of the notch 9, as shown at 13, to adapt the member 11 to coact with the under or exposed side of the stud 10 when within the arm notch 9 to resist a withdrawal of the arm 6 from engagement therewith. The oscillatory movements of the catch-member 11 are limited by 75 a stud 14 projecting from the arm 6 through a registering slot 15 in the catch-member.

The arm 9 is provided in a side edge thereof, in the present instance, above the stud 14, with a recess 16 the inner end wall of 85 which is provided with a projection 17 about which the inner end of the coiled compression spring 18 may be engaged, said spring being disposed within the recess 16 longitudinally of the arm 6 and having its 90 outer end fitting over a stud or tail-piece 19 projecting from the catch-member into the outer end portion of the recess 16, as shown. The spring 18 normally holds the catch-member 11 in one position relative to the 95 arm 6 and resists a releasing movement of the same from engagement with the stud 10. The outer end of the catch-member 11 is tapered or beveled similar to one of the beveled walls of the arm notch 8 to enable 100 the stud 10 to force the catch member outward against the tension of the spring 18 when such member and the arm 6 are lowered thereover.

Pivoted to each of the legs 4, as at 20, 105 is a gravity catch-member 21 having the arms *a* and *b* extending in diverging planes from its pivot with the free end of the arm *a* inwardly hooked to adapt it to have hooked engagement with stud 22, which 110

projects from the side of the frame section 1 between said arms. When the frame section 1 is in the folded reclining position shown in Fig. 2 and in full lines in Fig. 1, 5 the arm *b* of the catch-member, which arm is of greater weight than the arm *a*, has its lowering or gravity movements limited by an abutting of the inner end portion *c* of the catch member against the leg flange 4^a. 10 Likewise a swinging of the catch-member in the other direction is limited by the side *d* of the arm *b* striking against the leg flange 4^a. Upon a raising or continued folding movement of the section 1 with the section 15 2, the arm *b* of the catch-member, when the sections have been raised a predetermined distance, will act by gravity to move the hooked end of the arm *a* into hooked engagement with the stud 22, thus preventing 20 the leg 4, which is locked thereby, from swinging forward from the section 1 when the sections have reached the position shown in dotted lines in Fig. 1, or have passed beyond such position, upon a folding movement of the body-frame. Upon an unfolding movement of the bed-frame section it is evident that the catch-member 21 will move by gravity to stud releasing position when the sections 1 and 2 have reached a predetermined point in their unfolding movements 25 between the dotted and full line positions shown in Fig. 1, thus enabling the operator to unfold the legs 4 from the section 1 preparatory to raising the section 1 from over 30 the section 2, some force being necessary in such raising action due to the engagement of the catch means 6—11 with the studs 10 on the frame section 2.

In an unfolding of the bed-frame the 35 operator stands in advance thereof, and in the unfolding of the section 1 from the section 2 it is most convenient for him to grasp the opposite legs 4, 4 and to pull upward and forward on the same relative to the 40 catch means 6—11 with sufficient force to release such means from the respective studs 10. The catch-members 21 being automatic in their action need no attention on the part of the operator but stand in unlocked position relative to the respective studs 22 when the section 1 is folded in reclining 45 position over the section 2, and automatically act to lock such legs when the frame sections 1 and 2 have been raised a predetermined distance from their reclining 50 position.

I wish it understood that my invention is

not limited to any specific construction or arrangement of the parts except in so far as such limitations are specified in the claims. 60

Having thus described my invention, what I claim as new and desire to secure by Letters Patent, is,—

1. The combination with a foldable multiple section frame and a member carried by 65 one of the frame sections for pivotal folding movements relative thereto, of means carried by said member and automatically operable by gravity action to engage a part of the section carrying the member and to 70 secure the member and the section carrying the same in folded relation when the frame has been folded a predetermined extent and to release the section when the frame has reached a predetermined point in an unfolding movement thereof. 75

2. The combination with a section of a foldable bed frame, said section having a projecting part, and a supporting leg carried by said section for folding movements 80 thereto, of a catch-member pivotally carried by said leg and automatically operable by gravity action to engage said projecting part and lock the leg and section in folded relation at a predetermined point in 85 a folding movement of the frame and to release the leg from its locked position when the frame has been unfolded a predetermined extent.

3. The combination with a section of a 90 foldable bed-frame, said section having a projecting part, and a supporting leg carried by said section for folding movements thereto, of a catch-member pivotally the leg and having diverging arms project- 95 ing transversely from its pivot in position to straddle said projecting part, one of said arms being inwardly hooked to adapt it to swing into hooked engagement with said projecting part and the other arm being 100 of greater weight than the hooked arm to cause it to control by gravity action the engaging and releasing movements of the hooked arm relative to the projecting part whereby the catch is automatically engaged 105 with said part when the bed-frame has been folded a predetermined extent.

In testimony whereof, I have hereunto signed my name to this specification in the presence of two subscribing witnesses.

ADOLPH C. KLOPPING.
